UNITED STATES PATENT OFFICE.

JOSEPH COLONEL, OF NEW YORK, N. Y., ASSIGNOR TO RHINELANDER REFRIGERATOR CO., OF RHINELANDER, WISCONSIN.

DESIGN FOR A REFRIGERATOR.

40,838.

Specification for Design. Patented Aug. 23, 1910.

Application filed June 25, 1910. Serial No. 568,948. Term of patent 3½ years.

To all whom it may concern:

Be it known that I, JOSEPH COLONEL, a citizen of the United States, residing in the city of New York, borough of Brooklyn, in the county of Kings and State of New York, have invented a new, original, and ornamental Design for a Refrigerator, of which the following is a specification, reference being had to the accompanying drawing, forming part thereof.

The figure is a perspective view of a refrigerator, showing my new design.

I claim:

The ornamental design for a refrigerator, as shown.

JOSEPH COLONEL.
